UNITED STATES PATENT OFFICE.

LEANDER A. COGSWELL, OF MANCHESTER, NEW HAMPSHIRE, ASSIGNOR TO LACENE MANUFACTURING COMPANY, OF MANCHESTER, NEW HAMPSHIRE, A CORPORATION OF MAINE.

MARKING DEVICE FOR GRADING MACHINES.

Application filed May 9, 1925. Serial No. 29,079.

This application is a continuation in part of my application Serial No. 720,215, filed June 16, 1924, for a grading, fleshing and evening machine, and relates particularly to marking or stamping devices for use in a grading machine of the kind disclosed in my said former application and/or in the well-known Nichols grading machines of which an example is shown in the Nichols Patent 10 No. 1,130,321, dated March 2, 1915.

Since neither the grading machine as a whole, nor the mechanism for actuating the marker or stamp, in and of themselves constitutes any part of the present invention, it will 15 not be necessary to describe them here in detail, but merely to refer to said former disclosures for a complete description. Suffice it to say for the purpose of the present application that a grading machine to which the 20 present invention is applicable has means for detecting the grade of successive blanks of stock according to a thickness dimension, and a marker or stamp responsive to the detecting means for marking the blanks in accordance 25 with their grades as determined by the detecting means. The present invention has to do with the markers themselves, and more specifically to the combination of tannage marking wheels with the grade marking wheel, as 30 more fully hereinafter set forth.

A shoe manufacturer often wishes to have his soles, heel lifts or other blanks or pieces of stock which enter into the manufacture of shoes, stamped not only to indicate their 35 thickness grades but also to indicate the particular tannage of the leather of which they are made. Moreover, a manufacturer may use stock of a very large number of different tannages. It is the main object of the present invention to produce a marking or stamping device for a grading machine capable of 40 accomplishing this result.

In the accompanying drawings, which illustrate certain embodiments of the invention:—

Fig. 1 is a sectional view of one form of the marking device;

Fig. 2 is a front elevation of the grade marking wheel;

50 Figs. 3 and 4 are front elevations of the two tannage wheels shown in Fig. 1;

Fig. 5 is a sectional view of a modified form of the marking device;

Fig. 6 is a front elevation on line 6—6 of Fig. 5; and

Fig. 7 is detail of the form of detent used in the modification shown in Figs. 5 and 6.

Referring first to Figs. 1 to 4, the device comprises a grade marking wheel 10 provided with appropriate types on its salient, 60 peripheral projections 11 for stamping the grade marks on the pieces of stock as they pass through the machine. The grade marking wheel 10 is fixed to the end of a shaft 12, journaled in a supporting head 13, which is 65 in the form of a vertically sliding plunger, as explained in said earlier application and patent, and which at the proper times is forced downward to impress the marking on the stock. On the end of shaft 12 is a pinion 14 70 through which the grade wheel 10 is adjusted by means of the usual setting mechanism in response to the grade detecting means.

Loosely mounted on the same shaft 12, which carries the grade marking wheel 10, 75 and located in a recess milled in the side of the support 13, is a thin type wheel 15 similar in general outline to the grade marking wheel 10 but having stamping or marking characters on its peripheral projections to indicate tannages. An annular row of depressions or sockets 16 is provided on the inner face of wheel 15. Adjacent the main tannage wheel 15 is a supplemental tannage wheel 17 in the form of a segment below the center having a 80 contour similar to any segment of the main wheel 15, the upper part being cut away and provided with a row of depressions or sockets 18 arranged in the arc of a circle. A detent 19 is mounted in a hole in head 13 and is 85 yieldedly pressed by a spring 20 into engagement with one or another of the sockets 16 of wheel 15. A similar detent 21, mounted in another hole in head 13, is yieldedly pressed by spring 22 into engagement with one or 90 another of the sockets 18 of the wheel segment 17. The detent 19 projects through the space left by the cut away part of wheel segment 17.

As shown in the drawings, there are twenty type projections on the main tannage wheel 100 15, and eight type projections on the segment 17, the end projection 23 of the segment being left blank opposite the end socket 24. It will be understood that the operator sets the tannage wheels by hand to indicate a batch or 105 run of soles or blanks of any particular tan-

nage, the yielding detents retaining the wheels as set, and that the tannage wheels will remain set and will mark the soles for that tannage until changed by the operator; 5 but the grade measurements of the successive soles will be automatically marked on the soles by the grading wheel 10 in accordance with the grade detections. By using each of the types (twenty in number) of the main 10 tannage wheel 15 in conjunction with each of the types (eight in number) of the segment 17, the number of different tannages which can be indicated by the combinations of characters is one hundred and sixty; and by using 15 the main tannage wheel alone in conjunction with the blank 23 of segment 17, twenty more identifying marks can be used, making in all one hundred and eighty different designations for different tannages. Of course this 20 number can be varied at pleasure, within practicable limits, by varying the number of types on the two tannage wheels.

Referring now to the modification shown in Figs. 5 to 7, the supporting head 13, the grade 25 marking wheel 10, the shaft 12 and the pinion 14 may all be substantially as shown in the other figures. Tannage wheel 25 is similar to wheel 15 save that the peripheral notches 27 between the type projections are approximately rectangular, instead of curved, in order positively to engage the detent presently to be described. The other tannage wheel 26 is like tannage wheel 25, except that if desired the notches 27 in one wheel may be slightly 30 deeper than in the other. The two tannage wheels 25 and 26 are mounted to turn on a boss or hub 28 on one side of the support 13 concentric with shaft 12, and are held on the hub by an annular flange 29 screwed to the 35 end of the hub. A detent in the form of a slide 30 is mounted in a longitudinal channel in the support 13, with its lower end engaging one of the notches or depressions 27 of each tannage wheel 25 and 26. By making 40 the notches 27 of one wheel a little deeper than those of the other, and the locking end of detent 30 opposite the deeper notches a little longer, as shown at 31 (Fig. 7), than the 45 parts of the end opposite the shallower notches, the operator by lifting the detent far enough out of the notches to clear one tannage wheel, but not the other, may if he desires adjust one wheel while the other is held locked and undisturbed. A slight additional move-

ment of the sliding detent will free both 55 wheels for adjustment.

With the modification shown in Figs. 5 and 6, using two complete and unmodified type wheels it is possible to provide for a much larger number of tannage marks, using the 60 same size wheels, than with the form shown in Figs. 1 to 4. For example, if both wheels have a full and equal number of types, assumed to be twenty types as in the case of wheel 15 (Fig. 3), four hundred different 65 combinations are possible to designate tannages, as against one hundred and eighty permitted by the use of the segmental wheel 17 (Fig. 4). Moreover, the detent 30 by positively locking the tannage wheels in adjusted position prevents their being accidentally disarranged by shocks due to the actuation of the stamping device as a whole or by other causes. In either form of the device one tannage wheel 70 may be adjusted, while the other is held stationary by its detent.

I claim:

1. In a machine of the character described, in combination, a grade marking wheel, a support therefor, a plurality of tannage marking wheels mounted on said support and adjustable independently of said grade marking wheel and of each other, each tannage marking wheel having a series of peripheral notches, the notches in one wheel being deeper 80 than the notches in the other wheel, and a detent common to said tannage marking wheels and mounted to move on said support into and out of engagement with said notches, the locking end of said detent having a projection 85 cooperating with the deeper notches. 90

2. In a machine of the character described, in combination, a grade marking wheel, a support therefor, a plurality of other marking wheels mounted on said support and adjustable independently of said grade marking wheel and of each other, each such other marking wheel having a series of concentric locking sockets, one series being radially nearer the axis of the wheels than the other, and detent means movably mounted on said support to engage and disengage said sockets, whereby one of said other marking wheels 95 may be unlocked and adjusted without unlocking the other or others. 100

Signed by me at Manchester, New Hampshire, this seventh day of May, 1925.

LEANDER A. COGSWELL.
